Attorney

UNITED STATES PATENT OFFICE

WILLIAM G. SHELTON, OF ST. LOUIS, MISSOURI

HAIR-WAVING APPLIANCE

Application filed August 15, 1929. Serial No. 386,006.

My invention relates to the art of hair waving and consists in a novel heater, and clamping and heating structure to be used in the permanent waving of hair.

5 One of the objects of my invention is to provide a heater with a compact hair engaging means mounted thereon with no exposed spring parts to snag the hair.

Another object of my invention is to utilize 10 a flat spring for the handles without using the spring itself as a hinge element for the handles.

Another object of my invention is to provide 15 a means for producing waves closer to the scalp of the user than the devices of the prior art have been able to produce.

Another object of my invention is to protect 20 the scalp of the user from injury due to heating of metallic portions of my device or descent of moisture.

In the accompanying drawings which illustrate 25 a selected embodiment of my invention—

Figure 1 is an end elevation of the assembled structure.

Figure 2 is a side view of the same.

Figure 3 is a top view of the clamping structure.

Figure 4 is a vertical section taken on 30 the line 4—4 of Figure 2, showing the hair wound on the rod and the supply unit and heater applied over the same.

The heater member has an arcuate body 1 containing an electric resistance heating element and mounting a block 2 of insulating material on its convex surface. Spring clips 3 are attached to each side of the block 2 and each clip comprises an end portion secured to the top of the side of the block 40 by screws 4, or other suitable means, and a horizontal intermediate portion and an outer lower portion 5 spaced from the block 2 and below the same.

Separately formed arms 6 are mounted 45 upon the outer portions 5 of the spring clips and have inturned flanges 7 at the top that bear against the upper portion of clips 3 adjacent to where the same are secured to block 2. The lower portions of arms 6 form 50 wings 8 conforming to the contour of the

arcuate body 1 and terminate in jaws 9 extending under the lower edges of member 1. Jaws 9 are adapted to project to grip the strand of hair T and supply P. The jaws 9 are opened by means of handles 10 secured to arms 6 at 43 below inturned flanges 7 and projecting above flanges 7. By pressing the handles together above flanges 7, the jaws are pushed apart, flanges 7 acting as fulcrum bearings on the spring clips adjacent to where the same are secured to block 2. It will be understood that the spring clips 3 hold or tend to hold the jaws in the full line position shown in Figure 1, but the jaws may be opened to permit application or removal of the heater member to and from the cylinder-like body formed by the strand of hair wrapped about the rod 26 and enclosed in the supply P.

By mounting the arms 6 as shown, the structure is made more desirable to use as compared with devices which have exposed hinges and springs likely to snag the hair and as compared with the structure disclosed in my copending application, Serial Number 333,895, filed January 21, 1929.

In my present device, the handle fulcrum is independent of the spring and is at the upper end of the block, and the spring is of substantial length and the full length of the spring functions in closing the jaws. This is a better construction than that shown in my copending application in which the spring forms the fulcrum and only a restricted portion of the spring can flex.

Plugs 11 are provided in the top of block 2 for insertion into terminals of a heater cord where the same may be quickly disengaged from the heater in case of an emergency of any kind.

The scalp of the customer is indicated at S and T is a strand of hair. P is a supply pad. The strand will be gripped adjacent to the scalp by a clamping and curling member which is associated with the heater and hair engaging member and is adapted to engage and curl the hair between the heater and the scalp of the user.

The clamping and curling member referred to is composed of bars 12 and 13 of

bakelite or other suitable material which are hinged together at 15 by bar 16 secured to bar 13. Suitable catch elements, 17 and 18 are provided at the unhinged ends of bars 12 and 13.

5 Bar 12 has channel shaped horizontal faces and concave vertical faces and has a covering 19 of resilient material.

Bar 13 is mounted on a heat insulating member 20 adapted to rest on the scalp of the user and has a metallic member contacting with the bottom of the inner vertical face of bar 13 and secured to the upper horizontal face of the bar by rivets 21 or like means. 10 This metallic member forms a flange 22 extending between the vertical faces of bars 12 and 13 and is shaped to fit the contour of the rubber covered face of bar 12. The metallic member continues along the surface of the top horizontal face of bar 13 to form a folded tongue 23 and curves up from the top of the inside face of the bar 13 to form the curved flange 24.

25 Flanges 22 and 24, in conjunction with bar 12 are adapted to wave the strand T much nearer the scalp than is possible when using any of the devices of the prior art and even nearer than is possible when using the device disclosed in my copending application, Serial 30 Number 333,895 filed January 21, 1929.

The above clamping and curling structure is provided with a pawl 25 which is mounted on member 16. A curling rod shown at 26 has a ratchet 27 at one end which is engaged by 35 the pawl 25 as the rod is rotated to wind the hair. The engagement of the pawl and the ratchet prevents the rod from unwinding and loosening the roll of hair. The tension on the hair and the action of the pawl against the 40 ratchet are such as to hold the rod, wound with hair, against the clamp.

To apply the device to a strand of hair, the clamp is applied to the strand T close to the scalp S and bars 12 and 13 are locked together 45 by elements 17 and 18. The curling rod is then applied to the outer end of the strand and turned to wind the hair on the rod until the same is adjacent to the clamping jaws where the pawl 25 engages the ratchet 27 and 50 holds the rod 26 from unwinding when the same has been wound enough to create tension on the strand T. Then the supply element P is placed around the hair wound on the rod, and the lower edges of the supply 55 are pushed under the roll of hair so that the supply contacts with the metallic tongue 23. The heater is then placed over the supply. Heat from the heater then generates steam within the moist supply unit which heats the 60 metal member including flanges 22 to 24 whereby heat is applied to the strand of hair between the base of the clamp and the beginning of the outermost spiral of the roll of hair on rod 26.

65 The metallic flange 22 presses the hair

tightly into the recess formed by the rubber covered face of opposing jaw 12 to seal the clamping jaws so that no moisture can pass through the same to the scalp of the user. The felt pad 20 presses the hair tightly 70 against the rubber covering of the bottom of the face of jaw 12 to prevent the heat and moisture from passing from the flange 22 to the scalp of the user.

Obviously, many of the details of the described structure may be varied without departing from the spirit of my invention and I contemplate the exclusive use of all of such modifications as come within the scope of my claims.

75 I claim:

1. In a hair waving appliance, a member having a heat radiating surface, an insulating block mounted thereon, spring clips mounted on the sides of said block and near the top thereof and diverging from the base of said block, holding arms mounted on the lower portions of said clips and having downward extensions forming clamping jaws under said heat radiating surface.

2. In a hair waving appliance, a member having a heat radiating surface, an insulating block mounted thereon, spring clips mounted on the sides of said block and near the top thereof and diverging from the base of said block, holding arms mounted on the lower portion of said clips having downward extensions forming clamping jaws under said heat radiating surface and having upward extensions provided with inturned flanges bearing on said spring clips where the same are mounted on said block, and handles mounted on said arms and adapted to open said jaws.

3. In a hair waving appliance, a member having a heat radiating surface, an insulating block mounted thereon, spring clips mounted on the sides of said block and near the top thereof and diverging from the base of said block, holding arms mounted on the base of said clips having downward extensions forming jaws under said heat radiating surface and having upward extensions provided with inturned flanges bearing on said spring clips where the same are mounted on said block, and handles mounted on said arms to open said jaws by using said flanges as fulcrums.

4. In a hair waving appliance, a member having a heat radiating surface, an insulating block mounted thereon, spring clips mounted on the sides of said block and near the top thereof and diverging from the base of said block, holding arms mounted on the base of said clips having downward extensions forming jaws under said heat radiating surface and having upward extensions provided with inturned flanges, and handles mounted on said arms to open said jaws by using said flanges as fulcrums.

5. In a hair waving appliance, a member having a heat radiating surface, an insulating block mounted thereon, plugs for the application of a heater cord mounted in the top of said block, arms having clamping jaws extending below said heat radiating surface, and handles mounted on said arms and extending on both sides of said block to points above said plugs. 70
10. 6. In a hair waving appliance, a heater and a clamping and curling jaw comprising a bar of heat insulating material and a flange of heat conducting material mounted on said bar and adapted to be heated by said heater, 75 said flange describing a convex curve meeting the top and bottom of the inner surface of said bar.
15. 7. In a hair waving appliance, a heater and a clamping and curling structure comprising a bar of heat insulating material and a flange of heat conducting material mounted on said bar and adapted to be heated by said heater, 80 said flange describing a convex curve, and an opposing bar having a concave clamping surface opposed to said flange.
20. 8. In a clamp for a hair waving appliance, a bar having channel shaped top and bottom surfaces and concave sides. 85
25. 9. In a clamp for a hair waving appliance, a bar having channel shaped top and bottom surfaces and concave sides, said bar having a covering of resilient material. 90
30. 10. In a clamp for a hair waving appliance, a bar having an inwardly curving side, 95 said bar having a covering of resilient material adapted to conform to the contour of said side.
35. 11. In a clamp for a hair waving appliance, a bar having a convex hair engaging surface and an opposing bar having a concave hair engaging surface, the hair engaging surface of one of said bars being of heat conducting material and the hair engaging surface of the other of said bars being of 100 heat insulating material.
40. 12. In a clamp for a hair waving appliance, opposing bars, each having spaced convex hair engaging surfaces and a concave hair engaging surface between them, and each 105 bar having a convex surface opposite a concave surface of the opposing bar.
45. 13. In a clamp for hair waving appliance, a bar, a member mounted thereon having a plurality of convex hair engaging surfaces, one of said surfaces extending above the top of said bar. 110
50. 14. In a clamp for a hair waving appliance, opposed jaws, one of which jaws presents a plurality of convex hair engaging surfaces of heat conducting material to the other 115 jaw.
55. 15. In a clamp for a hair waving appliance, opposed jaws, one of which jaws presents a series of alternate convex and concave hair engaging surfaces to the other jaw. 120
60. 16. In a clamp for a hair waving appliance, opposed jaws, one of which jaws presents a plurality of convex hair engaging surfaces and a recess between them to the other jaw. 125
65. 17. In a clamp for a hair waving appliance, a bar, a member mounted thereon having a plurality of convex hair engaging surfaces of heat conducting material, one of said surfaces extending above the top of said bar. 130
70. 18. In a clamp for a hair waving appliance, a bar, a member mounted thereon having a plurality of convex hair engaging surfaces of heat conducting material, one of said surfaces extending above the top of said bar, and an opposing bar having a concave hair engaging surface of heat insulating material.
75. 19. In a clamp for a hair waving appliance, a bar, a member of heat conducting material mounted on the top of said bar, said member having upwardly and downwardly extending convex hair engaging surfaces. 135
80. 20. In an appliance for waving hair, a heater, a moist supply unit, a pair of clamping and curling jaws adapted to grip a strand of hair near the scalp of the user, one of said jaws comprising a bar, a member of heat conducting material having a plurality of convex hair engaging surfaces mounted on said bar, a portion of said member extending above said clamping jaws to engage the hair between said heater and said jaws, another portion of said member extending along the inside of said bar to engage the hair between said jaws, said supply unit engaging said member, said heater generating steam in said supply unit, said steam heating said member and thereby curling the hair engaged by said member. 140
85. 21. In an appliance for waving hair, a heater, a moist supply unit, a pair of clamping and curling jaws adapted to grip a strand of hair near the scalp of the user, one of said jaws comprising a bar, a member of heat conducting material mounted on said bar, a portion of said member extending above said clamping jaws to engage the hair between said heater and said jaws, another portion of said member extending along the inside of said bar to engage the hair between said jaws, the other of said jaws comprising a bar having a concave hair engaging face covered with a heat insulating resilient material, said supply unit engaging said member, said heater generating steam in said supply unit, said steam heating said member and thereby curling the hair engaged by said member. 145
90. 22. In an appliance for waving hair, a heater, a moist supply unit, a pair of clamping and curling jaws adapted to grip a strand of hair near the scalp of the user, one of said jaws comprising a bar, a member of heat conducting material mounted on said bar, a portion of said member extending above said clamping jaws to engage the hair between said heater and said jaws, the other of said jaws comprising a bar having a concave hair engaging face covered with a heat insulating resilient material, said supply unit engaging said member, said heater generating steam in said supply unit, said steam heating said member and thereby curling the hair engaged by said member, said jaws clamping the hair between them, the heat insulating resilient material covering the face of the second mentioned bar sealing the hair against the face of the first mentioned jaw to prevent the passage of heat or moisture to the scalp of the user. 150

22. In a device of the class described, a heater member, a block on the upper side of said member, a clip of spring material having one end secured to said block and the other end offset therefrom, and a holding arm secured to the latter end of said clip and extending below said heater and inwardly of the outer edge thereof to form a jaw for engaging a strand of hair.
23. In a device of the class described, a heater member, a block on the upper side of said member, a clip of spring material having one end secured to said block and the other end offset therefrom, and a holding arm secured to the latter end of said clip and extending below said heater and inwardly of the outer edge thereof to form a jaw for engaging a strand of hair and also extending above said heater to provide a handle where-
20 by the jaw may be moved transversely of the heater by compressing said clip.
24. In a device of the class described, a heater member, a block on the upper side of said member, clips of spring material on the opposite side of said block, each comprising an end secured to said block and a middle portion extending away from said block and another end portion substantially spaced from and below said block, and arms secured
25 to said latter mentioned portions and extending upwardly and downwardly therefrom, the upward extension of said arms forming handles and the downward extensions project-
30 ing beneath said heater member forming op-
35 posing jaws for gripping a strand of hair be-
tween them at points spaced apart a less dis-
tance than the spacing of said clip portions,
whereby the jaws may be moved laterally
into and out of hair engaging positions with
40 minimum vertical movement.

In testimony whereof I hereunto affix my
signature this 13th day of August, 1929.

WILLIAM G. SHELTON.
